UNITED STATES PATENT OFFICE.

JOHN C. HYLTON, OF CHICAGO, ILLINOIS.

HINGE.

1,022,588.

Specification of Letters Patent.

Patented Apr. 9, 1912.

Application filed May 18, 1911. Serial No. 627,902.

To all whom it may concern:

Be it known that I, JOHN C. HYLTON, a citizen of the United States, residing at Chicago, in the county of Cook and State of Illinois, have invented new and useful Improvements in Hinges, of which the following is a specification.

This invention relates to hinge constructions and more particularly to hinges for use in connection with hoods for automobile engines, although the invention is capable of use in connection with other bodies that are to be hinged together.

The object of this invention is to provide a hinge construction wherein the usual slits between the ears are omitted.

Another object is to provide a hinge of this character which does not require the addition of a separate pintle as is customary in the ordinary hinges.

To such ends this invention consists in the several novel features of construction, arrangement and combinations of parts hereinafter set forth and claimed.

The invention is clearly illustrated in the drawing furnished herewith in which—

Figure 1 is a perspective view of the hinge applied to the hood of an automobile engine, Fig. 2 is a detail vertical transverse section taken on the line 2—2 of Fig. 1 and showing one of the members of the hood in raised position, Fig. 3 is a detail horizontal section taken on the line 3—3 of Fig. 2, Fig. 4 is a detail fragmental perspective view of the two parts of the hinge, disconnected from each other, Fig. 5 is a fragmental perspective view of a slightly modified form of end finish for the hinge and Fig. 6 is an end view of the parts seen in Fig. 5.

Referring to said drawing, 10 represents a hood such as is ordinarily employed to cover the engine of an automobile. Said hood may be of any suitable form and in the form illustrated comprises two upright leaves 11, 11, and two top leaves 12, 12, hinged to the upright leaves 11, 11, and hinged at their adjacent edges to a stationary leaf 15, carried by a support which in this instance is illustrated in the form of a rod 13, arranged to be mounted on the radiator and dash of the automobile, as is customary. The lower edges of the upright leaves 11, are shown as flanged outward to make a finish along the lower edges of the leaves, and to reinforce and strengthen them

along those lines. A handle 14, is provided for each upright leaf 11, whereby the same and the top leaf may be lifted to expose the engine to view.

The detail construction of the hinge connection between the several leaves is best illustrated in Figs. 2 to 6, inclusive, and will now be described.

Secured to the supporting rod 13, as by rings 13^a, is the leaf 15, which in the present instance is shown as formed with a central downward bend 16, extending underneath the rod 13, and formed at the sides of said downwardly curved portion with approximately cylindrical portions 17, the edge of each cylindrical portion terminating a slight distance away from the downwardly curved portion 16, as illustrated at 18, so as to leave a slight gap 18^a, between said edge and the part that connects the downwardly curved portion 16, with the cylindrical portion 17. The other half of the hinge comprises a cylindrical portion 19, fitted to and capable of turning within the cylindrical portion 17, of the stationary leaf of the hinge, said cylindrical inner portion 19, being shown as formed upon the end of the leaf 12, by rolling the adjacent edge thereof into cylindrical form, of a diameter to fit within the cylindrical portion 17. The leaf 12, enters the outer cylindrical portion 17, through the gap 18^a, thus closing the same against the entrance of rain or snow and makes a comparatively tight joint between the two members of the hinge. The cylindrical portions 17, 19, form the ears of the hinge and turn one upon the other. The ends of the portion 16, are notched as at 16^a, for the reception of the rings 13^a.

The edges of the hinges may be trimmed and reinforced in suitable manner. Referring to Figs. 1, 3 and 4, a thimble 20, will be seen on the end of each ear, said thimble having a ring-like wall 21, surrounding each ear and being formed with an inturned flange 22, bearing against the inner face of the cylindrical member 19, of the ear. The ends of the leaves 12, are notched as at 12^a, at points adjacent to the ears to receive the wall 21, of the thimbles and if desired each thimble may be secured to the outer cylindrical member 17, of the ears by riveting them thereto, soldering them thereon or in any other suitable manner as may be desired.

In raising either leaf 12, from the position shown in solid lines in Fig. 1, to that shown in dotted lines, the inner cylindrical portion 19, turns within the outer cylindrical portion 17, the elasticity of the metal permitting the parts to yield in case of any unevenness therein.

The hinge between the leaves 11, 12, is substantially similar to that between the 10 leaves 12, 15, but in place of the thimble 20, I have shown a ring 23, surrounding the cylindrical portion 17, 19, of the hinge. The ends of the two leaves are notched as before to permit the ring to be slipped over the 15 cylindrical portions.

The device is particularly desirable when used upon a hood for covering automobile engines, because of its neatness in appearance and because there are no gaps or crevices through which rain or snow may pass. It is obvious that the hinges may be made of separate plates of material secured to the main leaves of the hood or may be made an integral part thereof as illustrated in the 25 drawing. The hinge may be applied in other situations where hinges are required, as for instance they may be used upon doors, boxes and the like, and I do not therefore desire to be understood as restricting my 30 invention for use in connection with a hood for automobiles.

I realize that various alterations and modifications of this device are possible without departing from the spirit of my invention, and I do not therefore desire to 35

limit myself to the exact form of construction shown and described.

I claim as new and desire to secure by Letters Patent:

1. A hinge comprising two companion leaves, each having the whole of one edge rolled into cylindrical formation, with each cylindrical edge partially wrapped around the other cylindrical edge, each cylindrical edge being of greater extent than a semi-circle, whereby the two leaves are held in pivotal connection at any desired angle with respect to each other.

2. A hinge comprising two companion leaves, each having one edge rolled into a cylindrical ear, with the cylindrical ear of one fitted within and turning in that of the other, and thimbles secured on the ends of the outer ears.

3. A hinge comprising two companion leaves, each having one edge rolled into a cylindrical ear with the cylindrical ear of one fitted within and turning in that of the other, each leaf having notches in its ends adjacent to the ears and thimbles secured on the ends of the ears and projecting into said notches.

In witness whereof, I have hereunto signed my name at Chicago, Cook county, Illinois, this 6th day of May 1911.

JOHN C. HYLTON.
